UNITED STATES PATENT OFFICE

2,604,038

APPARATUS FOR IMPRINTING DESIGNS ON
BUILDING BOARDS

William C. York, Alexandria, Va.

Application May 14, 1948, Serial No. 27,086

3 Claims. (Cl. 101—22)

1

This invention comprises novel and useful improvements in an apparatus for imprinting designs on building boards and more specifically pertains to an apparatus for printing, incising and imprinting ornamental designs or other matter upon building boards, panels or the like.

A primary object of this invention is to provide an apparatus for more efficiently imprinting a design in materials such as building boards or the like.

Another object of the invention is to provide an apparatus as set forth in the preceding object which may be readily adjusted to accommodate boards and materials of different thicknesses.

A still further object of the invention is to provide an apparatus having improved means for preventing damage to the device by the passage of a board of abnormal thickness therethrough.

An important feature of the invention includes the provision of a supporting table in the upper surface of which is journalled a plurality of feed rollers, and which table is provided with spaced supporting standards for journalling therebetween and over the table an imprinting roll. Another feature of the invention includes the provision of an apparatus as set forth in the foregoing feature accompanied by a pressure roll journalled in the surface of its supporting table below the imprinting roll for receiving material therebetween for imprinting a design therein.

A still further feature of the invention resides in the provision of a manually operated adjusting means for simultaneously raising or lowering and thereby varying the distance of the imprinting roll with respect to the pressure roll, in order to adapt the apparatus to accommodate boards and materials of different thicknesses.

A still further feature of the invention resides in the provision of an apparatus as set forth in the preceding paragraph, wherein the manual operating means for vertically adjusting the imprinting roll is conveniently mounted on the under surface of the supporting table.

A still further additional feature of the invention includes the provision of a novel means for actuating the power roll, which driving means is conveniently mounted beneath the supporting table and is connected to the power roll in such a manner as not to have its driving engagement interfered with or affected by the vertical adjustment of the manual means.

A still further important feature of the invention envisions and contemplates a resilient means for adjustably and yieldingly urging the imprinting roll towards the pressure roll, and for permitting retrogressive movement of the im-

2

printing roll when an abnormally thick object passes between the imprinting roll and the pressure roll, to thereby prevent damage to the device.

A further and important feature of the invention includes the provision of a compact and novel manner for mounting the bearing blocks supporting the imprinting roll in vertically disposed guides in the support standards, and wherein the bearing blocks are removable from the open upper ends of the vertical guide channels as desired.

And a final important feature and object of the invention to be specifically enumerated herein, resides in the provision of a simple, compact, sturdy but easily serviced and repaired construction for imprinting designs upon sheet material such as building boards or the like.

These, together with various ancillary features and objects of the invention which will later become apparent as the following description proceeds, are attained by this device, a preferred embodiment of which has been illustrated by way of example only in the accompanying drawings, wherein:

25. Figure 1 is a top plan view of a preferred embodiment of the invention;

Figure 2 is a bottom plan view of the same taken substantially upon the horizontal plane of the section line 2—2 of Figure 4;

Figure 3 is a vertical longitudinal sectional view taken substantially upon the plane of the section line 3—3 of Figure 1;

Figure 4 is a side elevational view of the invention as disclosed in Figures 1—3; and

Figure 5 is a vertical transverse sectional view taken substantially upon the plane of the section line 5—5 of Figure 1 and illustrating the bearing block construction, the adjustment therefor, the driving and the tensioning means of the imprinting roll.

40 Referring now more specifically to the accompanying drawings, wherein like numerals designate like parts throughout the various views, attention is directed first to Figures 4 and 5, wherein it will be seen that the principles of the invention may be most easily attained by providing a table of any suitable dimensions having a bed or supporting surface 10, mounted upon suitable legs 12 and provided with a bottom shelf 14 for a purpose to be later set forth.

50 As will be readily understood, the table will be of any desired height, width and length, in accordance with the particular material which is to be handled in the apparatus. Conveniently, the table will be of such length and width as to 55 easily accommodate fibre building boards, ply

wood or other laminated building boards, and any other desired building materials, it being evident that the principles of the invention are applicable to a wide variety of materials.

Suitably journaled in longitudinally spaced, laterally or transversely extending grooves 16, in the upper surface of the bed 10, are a plurality of feed rolls 18 which project slightly above the upper surface of the bed and form means to facilitate the feed of a board of material, indicated generally at 20 in Figures 3 and 5, over the surface of the table. Preferably substantially adjacent the mid point of the table, one of these grooves 16 has journaled therein a pressure roll 22 of any desired construction.

Laterally spaced vertically disposed supporting standards indicated generally at 24 and which may conveniently comprise an A-frame are suitably and rigidly supported in any detachable manner upon the table surface 10 adjacent the opposite sides thereof, for journaling therebetween in a position to overlie the pressure roll 22, the transversely extending imprinting roll 26. This imprinting roll may be of any desired construction and in itself forms no part of this invention, but it is contemplated that the same shall detachably receive a cylindrical or sleeve-like jacket 28, splined or otherwise secured thereto in a non-rotatable but removable manner, which member 28 upon its outer surface is provided with any suitable ornamental design or other indicia which it is desired to imprint upon the adjacent surface of the material 20 passing between the imprinting roll and the pressure roll.

On that side of the imprinting roll from which the sheet of material emerges, as shown in Figure 3, there are provided a pair of supporting brackets 30 and mounted upon the table surface 10, between which brackets is journaled a transversely extending hold-down roll 32 which is so positioned as to press downwardly upon the sheet of material emerging from between the imprinting roll and the pressure roll, to thereby prevent curling up of the end of the material, and compel the same to emerge in a straight or flat strip from the imprinting and pressure rolls.

As will be seen by reference to Figures 4 and 5, each of the A-frame supporting standards 24 includes a vertically disposed pair of spaced, channel members 34 which constitute vertical guideways that are open at their upper ends. Slidably received in these channel members 34, are bearing blocks consisting of lower blocks 36 and upper blocks 38, the adjacent surfaces of upper and lower blocks being provided with concave seats to receive the trunnions 40 of the axle 42 of the imprinting drum or roll 26. Thus, the imprinting roll rests by means of the trunnions 40 upon the lower bearing blocks 36, while the upper bearing blocks 38 rest upon the trunnions, and are yieldingly pressed downwardly thereon as set forth hereinafter.

Rotation of the imprinting roll is effected by any suitable power source such as an electric motor or the like 44, mounted upon the shelf 14, which motor by means of a spur gear 46 drives a gear 48 upon a shaft 50, this shaft 50 being further provided with a sprocket gear 52 which by means of a sprocket chain 54 and large sprocket gear 56, mounted on an extension of one of the trunnions 40, serves to rotate the imprinting roll. Slack in the sprocket chain which is necessary in order that the imprinting roll may be vertically adjusted relative to the pressure roll as set forth hereinafter, is taken up

as by means of an idler sprocket 58, mounted on an adjusting bracket 60 which is secured to the side of the table 10 and is manually adjustable longitudinally thereof in any desired manner.

Attention is now directed specifically to Figure 5, wherein it will be seen that the upper surface of the table 10, is provided with metallic bed plates or the like 62, from which depend by means of bolts 64, U-shaped supporting brackets 66 secured to the under surface of the table. The bed plates 62 may be conveniently provided with upwardly extending bosses 67 which are tubular and which constitutes guides to receive vertically disposed adjusting screws 68 which extend entirely through the bed plate 62, the supporting bracket 66, and at their upper ends support and carry the lower blocks 36, while their lower ends extend below the table.

Received in and supported by the brackets 66, are driven gears 70, which are non-rotatably but slidably secured upon the adjusting screws 68 as by splines or the like, not shown. As will be more clearly apparent by reference to Figure 2, these driven gears 70 are each constantly in mesh with a worm gear 72 non-rotatably secured to the opposite ends of a transverse shaft 74, provided with an intermediate bevel gear 76 engaged by a corresponding miter or bevel gear 78 affixed to the end of an adjusting shaft 80 suitably attached as by brackets 82 to the under surface of the table 10, and which shaft is provided with a crank 84 whereby the shaft may be manually adjusted to simultaneously rotate the driven gear 70 and thereby simultaneously raise or lower the adjusting screw 68 to uniformly vertically adjust the lower bearing blocks 36 in their guide channels in the A-frames 24. By this means, imprinting roll may be vertically raised or lowered evenly, with respect to the pressure roll, whereby the desired clearance may be introduced therebetween to accommodate any given material or board to be ornamentally imprinted.

It should be here noted that because of the idler pulley construction 58 and 60, the vertical adjusting means of the imprinting roll may be effected without disturbing the driving engagement between the motor 44 and the imprinting roll.

As shown best in Figure 5, a transverse bar 86 extends between the two A-frames 24, and is retained by means of pivoted cap plates 88 which are terminally pivoted as at 90 to one side of the A-frame, and are detachably pinned or secured as at 92 to the other side thereof. A transverse leaf spring 94 is provided having its ends extending within the vertical guide channels and bearing upon the upper surface of the upper bearing blocks 38, the mid portion of this transverse spring being rotatably secured to an adjusting screw 96 threaded through the transverse bar 86, which adjusting screw is provided with a manual crank 98 by means of which the center portion of the leaf spring 94 may be raised or lowered to thereby vary its pressure upon the bearing blocks 38. As will be readily understood, the spring may be adjusted to provide any desired load upon the imprinting roll, whereby the roll is free to move vertically and yield in response to an abnormal obstruction or thickness of material passing between the same and the pressure roll.

As will be readily understood, suitable bracing of any desired type may be provided for rigidly securing the components of the A-frames to each other. One convenient cross bracing may consist of the crossed braced bars 100 (see Figure 1)

which are terminally secured to the opposite A-frames, and are intermediately secured to each other as at 102.

The operation of the apparatus is as follows: With the imprinting roll properly adjusted vertically of the pressure roll, a sheet of material 20 is fed between the pressure and imprinting roll, and as the same passes therethrough, the power operated imprinting roll serves to feed the sheet of material, which is thereby imprinted with and marked by the design or indicia appearing upon the removable and replaceable cylindrical jacket 28. Obviously, it is merely necessary to remove and replace this jacket in order to adapt the device to imprint a different design for ornamenting or embellishing building materials or the like. As the sheet of material emerges from the imprinting and pressure rolls, the same is prevented from curling up at the end and is restrained in its original flat shape by means of the hold-down roll 32.

As above mentioned, the imprinting roll may be vertically adjusted by the manual adjusting means above described, to vary the clearance between these rolls for accommodating different thicknesses of boards to be imprinted.

Should an unusually thick piece of material accidentally pass between the rolls, the imprinted roll be lifted, the upper bearing blocks 38 sliding in their vertical guideways against the resistance of the spring 94 to permit this, whereby the thick material may pass through without damaging the rolls.

When it is desired to remove the imprinting roll either for servicing the same or for placing the sleeve 28 thereon, it is merely necessary to remove the cap plates 88, the transverse beam 86 and the spring 94, whereupon a wedge having an inclined surface may be passed between the pressure and imprinting rolls. The passage of this wedge will lift the imprinting roll and its upper blocks 38, and if the wedge so chosen is of sufficient vertical thickness, blocks 38 will be lifted from the open upper ends of the guideways between the members 34, and the trunnions 40 will be likewise removable therefrom. At the servicing or repair, the imprinting roll may be returned to the guideways in similar manner.

From the foregoing, the manner of constructing and operating the device will be readily understood and further explanation is believed to be unnecessary. However, since numerous changes will readily occur to those skilled in the art after a consideration of the foregoing specification and accompanying drawings, it is not desired to limit the invention to the exact construction and arrangement shown and described, but obviously all suitable modifications and equivalents may be restored to, falling within the scope of the appended claims.

Having described the invention, what is claimed as new is:

1. In a design imprinting apparatus, a support surface having a pressure roll journaled thereon, spaced support standards on said surface, an im-

printing roll, a pair of bearing blocks vertically slideable in each of said standards and having concave seats in the adjacent faces of said blocks journaling said imprinting roll therebetween, regulating means for simultaneously adjusting the lower of said bearing blocks to regulate the clearance between said imprinting and pressure rolls, driving means for rotating said imprinting roll, said regulating means including a vertical screw carried by said surface and engaging each of said lower bearing blocks, a driven gear secured to each screw, gearing connecting said driven gears for simultaneous manual operation, and resilient means urging the upper bearing block against the lower at each side.

2. In a design imprinting apparatus, a support surface having a pressure roll journaled thereon, spaced support standards on said surface, an imprinting roll, upper and lower bearing blocks vertically slideable in said standards, complementary concave seats in the adjacent faces of the blocks journaling said imprinting roll therebetween, regulating means for simultaneously adjusting said lower bearing blocks to regulate the clearance between said imprinting and pressure rolls, driving means for rotating said imprinting roll, said regulating means including vertical screws carried by said surface and engaging each of said lower bearing blocks, a driven gear secured to each screw, gearing connecting said driven gears for simultaneous manual operation, and resilient means urging said upper bearing blocks against the lower, and including a bracket carried by and depending from said surface for supporting each driven gear, said vertical screws being non-rotatably but slidably connected to said driven gears.

3. In a design imprinting apparatus, a support surface having a pressure roll journaled thereon, spaced support standards on said surface, an imprinting roll, upper and lower bearing blocks slideable in each of said standards, concave bearing seats in the adjacent surfaces of the blocks, said imprinting roll being journaled in said seats, regulating means for simultaneously adjusting the lower bearing block to regulate the clearance between said imprinting and pressure rolls, spring means for yieldingly urging said upper blocks into pressure engagement with said lower blocks at each side.

WILLIAM C. YORK.
